ATTORNEYS.

UNITED STATES PATENT OFFICE.

GEORGE E. CAMP, OF UTICA, NEW YORK, ASSIGNOR TO THE FOSTER BROTHERS MANUFACTURING COMPANY, OF SAME PLACE.

DESIGN FOR A MATTRESS-FRAME.

SPECIFICATION forming part of Design No. 30,326, dated March 7, 1899.

Application filed December 31, 1898. Serial No. 700,862. Term of patent 7 years.

To all whom it may concern:

Be it known that I, GEORGE E. CAMP, a citizen of the United States, residing at Utica, in the county of Oneida and State of New York, have invented and produced a new and original Design for a Mattress-Frame, of which the following is a specification, reference being had to the accompanying drawings, forming a part thereof.

Figure 1 shows a perspective view of a mattress-frame of my design. Fig. 2 shows an end view of a corner of the frame on an enlarged scale. Fig. 3 shows a side view of the same. Fig. 4 shows a perspective of the same.

The feature of the design is the form, shape, and arrangement of the parts constituting the mattress-frame—viz., the corner-piece 1, having a cylindrical lower portion and a rec-

tangular upper portion, the round side rail 2 in line with the cylindrical portion of the corner-piece, the overhanging cross-bar 3 on the upper portion of the corner-piece, and the projecting pin 4, all substantially as set forth.

Having described my invention, what I claim as new, and desire to secure by Letters Patent, is—

The design for a mattress-frame, substantially as herein shown and described.

In witness whereof I have hereunto affixed my signature, in the presence of two witnesses, this 28th day of December, 1898.

GEORGE E. CAMP.
